UNITED STATES PATENT OFFICE.

EDWARD CLIFF, OF NEWARK, NEW JERSEY.

DOOR CHECK AND CLOSER.

SPECIFICATION forming part of Letters Patent No. 654,304, dated July 24, 1900.

Application filed April 23, 1900. Serial No. 13,880. (No model.)

To all whom it may concern:

Be it known that I, EDWARD CLIFF, a citizen of the United States, and a resident of Newark, in the county of Essex and State of New Jersey, have invented certain new and useful Improvements in Door Checks and Closers, of which the following is a specification.

The invention relates to improvements in door checks and closers; and it consists in the novel features, arrangement, and combinations hereinafter described, and more particularly pointed out in the claims.

My invention relates to the class of door closers and checks containing within a casing a coiled spring, a checking medium, and a central spindle, the upper end of the latter being connected by lever-arms with the lintel over the door, and the said spring being reversible, so as to adapt the device for right and left hand doors.

My invention has for its object to simplify and render more useful, durable, and positive this class of door closers and checks, as well as to avoid the inconveniences of their adjustment and the necessity of reversing the position of their springs when adapting them from a left to a right hand condition.

In carrying my invention into effect I make use of two springs, reversely coiled, one spring acting to close the door and the other as a check to prevent the slamming of the door, and said springs thus arranged serving to adapt the device for either right or left hand doors at will, it being only necessary in shifting from a right to a left hand door to adjust the tension of the springs so that the then-closing spring shall have sufficient force to handle the door and the checking-spring only the strength necessary to prevent the undue slamming of the door.

The door closer and check of my invention may or may not comprise a liquid or air checking medium in addition to the checking-spring.

The invention will be fully understood from the detailed description hereinafter presented, reference being had to the accompanying drawings, in which—

Figure 1 is a top view, partly broken away, of a door check and closer constructed in accordance with and embodying my invention. Fig. 2 is a central vertical longitudinal sec-

tion of same on the dotted line 2 2 of Fig. 1. Fig. 3 is a detached central vertical section of the sleeve on the actuating-spindle, with 55 the toothed wheel carried on the upper end of said sleeve, said sleeve being adapted to be engaged by the inner end of one of the coiled springs. Fig. 4 is horizontal section of same on the dotted line 4 4 of Fig. 3. Fig. 5 is a 60 sectional view, corresponding with Fig. 3, of the auxiliary sleeve which fits upon the sleeve shown in Fig. 3 and is engaged by the inner end of the other coiled spring. Fig. 6 is a horizontal section of same on the dotted line 65 6 6 of Fig. 5; and Fig. 7 is a central vertical section of the door check and closer corresponding with Fig. 2, but omitting the liquid-cylinder and the springs, Fig. 7 being presented to illustrate the form of casing which 70 will be employed when the liquid checking medium is omitted and the checking is to be done by one of the springs.

In the drawings, 10 designates the main exterior casing; 11, the central actuating-spindle; 12 and 13, respectively, the springs for effecting the closing and checking of the door; 14, a cap for closing the upper end of the casing 10; 15, a liquid checking-cylinder whose piston 16 is connected by a piston-rod 17 with 80 the eccentric 18, carried by said spindle 11; 19, a sleeve freely mounted upon the spindle 11 and receiving the inner end of the spring 13; 20, the auxiliary sleeve mounted freely upon said sleeve 19 and receiving the inner 85 end of the spring 12; 21, a toothed wheel secured upon the upper end of the sleeve 19, and 22 a similar wheel formed upon the upper end of the sleeve 20, said toothed wheels 21 and 22 being respectively engaged by the 90 pawls 23 and 24, pivotally secured to the lever-arm 25, which is of usual construction in this art and is fastened upon the upper end of the actuating-spindle 11.

The main casing 10 is provided within its 95 lower portion with a socket 26 to receive the lower end of the actuating-spindle 11, and the said casing 10 at a proper distance above said socket 26 is formed at opposite sides with the horizontal shelves or flanges 27 to afford 100 a support for the outer edges or portions of the lower spring 13.

The sleeve 19 is formed at its lower edges with the annular shoulder or flar e 28, which

affords a support for the inner portions of the lower spring 13, and said sleeve 19, above said annular shoulder or flange 28, contains a vertical recess 29 to receive the inner end of the lower spring 13. About on a level with the upper edges of the lower spring 13 the sleeve 19 is formed with the annular shoulder 30 to receive the lower end of the auxiliary sleeve 20, which, as shown in Figs. 2 and 7, fits upon the upper portion of the sleeve 19 and is formed with a vertical recess 31 to receive the inner end of the upper spring 12.

The actuating-spindle 11, sleeve 19, and sleeve 20 extend upward above the closing-cap 14, and upon the upper end of the sleeve 19 is secured the toothed wheel 21, while upon the upper end of the sleeve 20 is formed the corresponding toothed wheel 22, said wheels 21 and 22 being directly one below the other and adjacent to the upper end of the said spindle 11, said wheels 21 and 22 being thus in convenient position to be respectively engaged by the pivoted pawls 23 and 24, carried by the operating-lever 25. The pawls 23 and 24 are independent of one another, said pawls being freely secured upon the rivet 32.

The exterior casing 10 is at its inner vertical side formed with a recess 33 of customary form in this art to receive the outer ends 30 of the springs 12 and 13, while the inner ends of said springs respectively engage, as hereinbefore described, the recesses 31 and 29 of the sleeves 20 and 19.

Intermediate the coiled springs 13 and 12 35 I preferably provide a disk or washer 34, whose function is simply to separate the adjoining edges of the springs 12 and 13 and prevent the coils of one spring from interfering with the coils of the adjacent spring.

40 The liquid-cylinder 15 is in the form of a cup screwed within the threaded flange 34', formed on the casing 10, and said cylinder 15 has by preference tapered inner walls 35, said walls gradually converging toward the outer 45 end of said cylinder. The piston 16, contained within the cylinder 15, has tapered side walls 36, corresponding with the tapered walls 35 of said cylinder, and said piston 16 is adapted when at the outer end of its movement to engage said walls 35 of the cylinder 15. The piston 16 is provided with a port 37, containing the ball-valve 38, said valve closing said port during the outward stroke of the piston 16 and opening said port during 55 the inward stroke of said piston. During the inward stroke of the piston 16 its side walls gradually separate from the side surfaces of the cylinder 15 and allow a free passage of the oil or other liquid to the outer end of the 60 cylinder 15; but during the outward movement of said piston 16 its side walls approach the inner surfaces of the cylinder and more and more contract the passage of the liquid to the inner end of said cylinder, whereby 65 said liquid is caused to check the outward motion of said piston 16 and operate to cushion

ion or control the door during its closing movement. The side surfaces or walls 36 of the piston 16 are elongated and serve during the closing of the door to squeeze the liquid 70 outward against the inner surfaces of the cylinder 15, whereby, as I have discovered, a very desirable checking action may be secured. The piston 16 is pivotally secured to the outer end of the piston-rod 17, which at 75 its inner end is apertured to receive the eccentric 18, carried by the actuating-spindle 11. Above the eccentric 18 is provided the annular shoulder 39, which affords a stop 80 against any upward play at the inner end of the piston-rod 17 and a support for the lower end of the sleeve 19, as illustrated in Fig. 2.

The door check and closer presented in Fig. 7 corresponds with the door check and closer shown in Figs. 1 and 2, with the exception 85 that the liquid-cylinder and its coöperating parts are omitted from Fig. 7.

In the employment of my invention the casing 10 will be secured to the door as usual and the customary lever-arms will connect 90 the upper end of the spindle 11 with the lintel over the door. The springs 12 and 13 will be adjusted by rotating the sleeves 20 and 19, and one of said springs will by the winding of its sleeve be given sufficient force to properly close the door, said force varying, of course, with the weight of the door and other conditions, whereas the other one of said springs will have an independent adjustment by the winding of its sleeve, said other spring 100 being only wound sufficiently to enable it to operate as a cushion and prevent the closing-spring from slamming the door. It may be assumed, for instance, that the apparatus is applied to a right-hand door and that the spring 105 13 is operating as the closing-spring, while the spring 12 is then serving as the checking-spring, and under these conditions the spring 13 will have been given a much stronger tension than the spring 12 in order that the spring 110 12 may simply serve to check the action of the spring 13 without preventing the latter from firmly closing the door. Should it now be desired to apply the apparatus to a left-hand door, the tension of the spring 12 will 115 be increased and the tension of the spring 13 decreased, whereby the spring 12 will then be enabled to operate to close the door, while the spring 13 will serve as the checking-spring. The springs 12 and 13 are connected with independent sleeves 20 and 19 and each is capable of independent adjustment or winding to increase or decrease its tension. The springs 12 and 13 may be wound or unwound 120 at will to vary their tension by means of an instrument applied to the toothed wheels 21 and 22, connected with said sleeves, and in view thereof the closing-spring may be adjusted to the weight of the door it is to handle and with respect to the particular speed it 125 may be desired said door shall move in its closing action, while the checking-spring may 130

be readily adjusted to a nicety for the purpose of applying just the desired resistance to the closing action of the door.

The apparatus possessing the spindle and the reversely-coiled independent springs, hereinbefore described, presents a complete combined door check and closer and may be employed without the use of any liquid or air checking medium to aid or be aided by the checking-spring in controlling the checking action of the door. In Figs. 1 and 2 I present, however, an apparatus which in addition to the reversely-coiled springs 12 and 13 contains a liquid checking-cylinder 15, with its piston 16, and when such liquid-cylinder is employed the lower part of the casing 10 will be supplied with a suitable oil or other liquid of known character in this art. When the liquid checking medium is employed, the action of the piston 16 against the liquid during the closing of the door will serve to aid the checking-spring in resisting the closing movement of the door, or, expressed in other words, the liquid medium will resist the closing action of the door and will be aided by the checking-spring in such operation. It will not be necessary in all cases to employ the liquid checking-cylinder 15, and hence in Fig. 7 I illustrate the form of casing which will be employed when said liquid checking-cylinder is omitted. I do not confine the invention to the employment of a checking medium as an aid or to be aided by the checking-spring; but in some instances it will be desired to employ the liquid checking-cylinder in combination with the closing and checking springs. The springs 12 and 13 must be wound in reverse directions during their adjustment, and during the closing of the door the closing-spring 40 will unwind, while the checking-spring will be wound up and create the proper resistance.

What I claim as my invention, and desire to secure by Letters Patent, is—

1. The casing, the spindle, the lever thereon, and the pawls carried by said lever, combined with the independent sleeves on said spindle, the toothed wheels connected with said sleeves and adapted to be engaged by said pawls, and the reversely-coiled springs 50 engaging said sleeves and casing; substantially as set forth.

2. The casing, the spindle, the lever thereon, the pawls carried by said lever, the independent sleeves on said spindle and engaged 55 by said pawls, and the reversely-coiled springs engaging said sleeves and casing, combined with the checking-cylinder, and the piston therein operatively connected with said spindle; substantially as set forth.

3. In a door check and closer, the reversely-coiled springs both under tension, and means connected with said springs for their independent adjustment whereby the closing-spring may be given a greater tension than 65 the checking-spring, combined with the piv-

otally-mounted lever-arm, and means for connecting both of said springs to said arm, one of said springs serving as a closing-spring and the other as a checking-spring for right-hand doors, and likewise but in the reverse order 70 for left-hand doors; substantially as set forth.

4. In a door check and closer, the reversely-coiled springs both normally under tension and the tension of one of said springs being greater than the tension of the other spring, 75 combined with the pivotally-mounted lever-arm connected with both of said springs, the spring having the greater tension serving as the closing-spring, and the other spring serving as the check to prevent the slamming of 80 the door; substantially as set forth.

5. The casing, the spindle, and the lever thereon, combined with the independent sleeves on said spindle, the wheels 21, 22, connected with said sleeves, the reversely-coiled springs engaging said sleeves and casing, and means for connecting either of said 85 wheels with said lever-arm to cause either of said springs to serve as the closing-spring; substantially as set forth.

6. The casing, the pivotally-mounted lever-arm, the spindle for said arm, and the reversely-coiled springs within said casing, combined with the wheels 21, 22, loose on said spindle and disposed upon the top of said casing and respectively connected with the said 95 springs, and means for connecting either of said wheels with said lever-arm to cause either of said springs to serve as a closing-spring; substantially as set forth.

7. The casing, the pivotally-mounted lever-arm, the spindle receiving at its upper end the said arm, the reversely-coiled springs within said casing, the wheels 21, 22, loose on said spindle and disposed upon the top of 105 said casing and respectively connected with the said springs, and means for connecting either of said wheels with said lever-arm to cause either of said springs to serve as a closing-spring, combined with the checking-cylinder, and the piston therein operatively connected with said spindle; substantially as set forth.

8. In a door check and closer, the oppositely-arranged springs normally under different tensions, and connections for increasing the tension of the closing-spring and decreasing the tension of the checking-spring during the opening of the door, and for gradually restoring the normal tension of the said 120 springs during the closing of the door; substantially as set forth.

Signed at New York, in the county of New York and State of New York, this 21st day of April, A. D. 1900.

EDWARD CLIFF.
